E. McKEAN.

SLIDING DOOR LOCK.

APPLICATION FILED DEC. 26, 1902.

NO MODEL.

UNITED STATES PATENT OFFICE.

EDWARD MCKEAN, OF ST. LOUIS, MISSOURI.

SLIDING-DOOR LOCK.

SPECIFICATION forming part of Letters Patent No. 739,903, dated September 29, 1903.

Application filed December 26, 1902. Serial No. 136,682. (No model.)

To all whom it may concern:

Be it known that I, EDWARD MCKEAN, a citizen of the United States, residing in the city of St. Louis, in the State of Missouri, have invented certain new and useful Improvements in Sliding-Door Locks, of which the following is a full, clear, and exact description, reference being had to the accompanying drawings, forming part of this specification.

My invention relates to a lock for sliding doors in which provision is made for movement of the lock-catch in a manner to throw it into perfect engagement with the keeper carried by a sliding door mating with that by which the lock is carried or by a door-jamb to which the lock-carrying sliding door is moved. My construction also provides for the retention of the catch after it has been placed in locking engagement with its receiving-keeper, thereby securely holding it from disengagement with the keeper.

The invention consists in features of novelty hereinafter fully described, and pointed out in the claims.

Figure I is a face view of one side of the exterior of my lock applied to a door. Fig. II is a vertical section taken through a pair of doors or a door and jamb, the lock mechanism interior of its casing being shown in elevation. Fig. III is a vertical cross-section taken on line III III, Fig. II. Fig. IV is a horizontal section taken on line IV IV, Fig. II. Fig. V is a perspective view of the lock-catch and the bolt by which it is carried. Fig. VI is a perspective view of the catch-lifting trigger. Fig. VII is a perspective view of the rear end of the catch-bolt-supporting guide. Fig. VIII is a perspective view of the throw-plate and ribs by which the catch-bolt and catch are operated.

A designates a door in which my lock is seated, and A' is a second door mating with the door A or a door-jamb to which the door A is moved.

1 designates a keeper fitted to the door or jamb A' and provided with a catch-receiving orifice 2.

3 designates an edge face-plate fitted to the door A and provided with a catch-orifice 4. 50

5 designates side face-plates secured to each side of the door A to inclose the lock seated between them. These face-plates are provided with elongated openings 6 and keyholes 7. Back of each face-plate at the locations 55 of the openings 6 are recessed slides 8, which are laterally movable with respect to the side face-plates and are held for their sliding movement by lugs 9. (See Fig. III.)

10 designates a lock-casing set into the door 60 A between the face-plates and provided with keyholes 7^a, that register with the keyholes 7 in the side face-plates.

11 is an upper guide-rib, and 12 is a lower guide-rib, both of which are within the casing 10. 65

13 is a notch in the guide-rib 12, to which more particular reference will hereinafter be made.

14 is a guide fixed to the casing 10 and located slightly above the guide-rib 12 to furnish a space between the two members. This guide 14 bears at its upper side forward of its rear end a shoulder 15 and is provided at the rear of said shoulder with a socket 16, having 70 an incline at its rear side.

17 designates slidable throw-plates seated in openings 18 in the side walls of the casing 10, (see Figs. II and IV,) and 19 and 20 are slide-ribs carried by said throw-plates, the former 80 of which is movably situated between the lower fixed guide-rib 12 and guide 14, while the latter rests movably on the upper fixed guide-rib 11.

21 is a socket in the slide-rib 20, that receives interlocking engagement with a member to be hereinafter mentioned.

22 designates holes extending through the throw-plates 17 and the slide-ribs 19 and 20 and which receive pins 8^a, that are carried by 90 the slides 8 at each side of the lock for the purpose of connecting the throw-plates and slide-ribs to said slides to occasion movement of said slide-ribs when the slides 8 are shifted.

23 is a catch-carrying bolt movably seated 95 on the guide 14 and provided with a shoulder

24, adapted for movement to the shoulder 15 on said guide. At the rear end of said bolt is a downturned tongue 25, adapted for movement into and out of the socket 16 in the 5 guide 14.

26 is a spring fixed to the casing 10 and having its free end resting upon the bolt 23.

27 is a catch of hook form connected to the bolt 23 by a pivot-pin 28. The catch 27 extends through the orifice 4 in the edge face-plate 3 of the lock and is adapted to be projected through the orifice 2 in the keeper 1 when the door is locked, as seen in Figs. II and IV.

15 29 is a spring by which the catch 27 is normally depressed and which is situated between the top side of the catch and an arm 30, carried by one of the throw-plates 17.

31 is a notched bracket carried by the throw-20 plate 17, which carries the arm 30.

32 is a lift-trigger mounted at its rear end upon the pivot-pin 28, that connects the catch 27 to its bolt 23. This trigger is provided at its rear end with a lug 33, that engages in the 25 notch of the bracket 31. At the forward end of the trigger is an arm 34, that extends beneath the catch 27, as seen in Fig. VI.

35 is a notched retaining-bolt located in the upper part of the lock-casing 10 and arranged 30 in guides at right angles to the upper slide-rib 20. This retaining-bolt is adapted to receive the engagement of a key 36, introduced through the keyholes 7 and 7^a in the face-plates and lock-casing, by which the bolt is 35 thrown into the socket 21 in said slide-rib when the catch 27 is in projected position and engaged with the keeper 1, to which it is moved.

37 designates turn-buttons extending, 40 through the slides 8, into the lock-casing 10 beneath the lower fixed guide-rib 12. On the stem of each turn-button, within said lock-casing, is a finger 38, adapted to enter the notch 13 in said guide-rib when rocked in an 45 upwardly direction and which when positioned in said notch serves to hold the slides 8 from lateral movement to actuate the throw-plate 17, thereby preventing actuation of the catch 27 after it has been locked.

50 The operation to actuate the catch 27 may be stated as follows: Assuming the latch to be engaged with its receiving-keeper, upon rearward movement of either of the slides 8 the throw-plates 17 and their slide-ribs 19 and 55 20 are shifted rearwardly. In this action the catch-carrying bolt 23 is held depressed by the spring 26 to ride on the guide 14, and as it starts to move thereon sufficient friction is occasioned by the bearing of the tongue 25 in 60 the socket 16 to slightly retard the movement of the bolt. The result is that the throw-plates and their ribs move a short distance without moving the bolt 23, and thereby rock

the lift-trigger 32 on its pivot and cause it to elevate the catch 27 from the position in 65 which it was held in engagement with its receiving-keeper by the spring 29. After the trigger has raised the catch continued pull upon the slide 8 moves the bolt 23 rearwardly and the catch is withdrawn from the keeper 70 and into the lock-casing. A reverse movement of either of the slides 8 again projects the catch, so that it may engage the keeper 1.

In the lower part of the lock-casing 10 I have shown a trip-handle mechanism, such 75 as is used in sliding-door locks, but for which no invention is herein claimed and of which, in view thereof, detailed description is deemed unnecessary.

I claim as my invention—

1. In a sliding-door lock, the combination 80 of a throw-plate, a slidable bolt, a catch pivoted to said bolt, and means connecting said catch to said throw-plate, substantially as and for the purpose set forth.

2. In a sliding-door lock, the combination 85 of a throw-plate, a slidable bolt, a catch pivoted to said bolt, and a trigger pivoted to said bolt and having engagement with said throw-plate and said catch, substantially as set 90 forth.

3. In a sliding-door lock, the combination 95 of a throw-plate, a slidable bolt, a spring-pressed catch pivoted to said bolt, and a trigger pivoted to said bolt and having engagement with said throw-plate and said catch, substantially as set forth.

4. In a sliding-door lock, the combination 100 of a throw-plate, a slidable bolt, means for retarding said bolt at a period of its movement, a catch pivoted to said bolt, and a trigger pivoted to said bolt and having engagement with said throw-plate and said catch, substantially as set forth.

5. In a sliding-door lock, the combination 105 of a throw-plate, a slidable bolt, a guide containing a socket on which said bolt is mounted, a spring pressing upon said bolt to cause it to engage in the socket in said guide, a catch pivoted to said bolt, and a trigger pivoted to 110 said bolt and having engagement with said throw-plate and said catch, substantially as set forth.

6. In a sliding-door lock, the combination 115 of a throw-plate, a slidable bolt provided with a tongue, a bolt-supporting guide provided with a socket adapted to receive said tongue, a spring resting upon said bolt, a spring-pressed catch pivoted to said bolt, and a trigger pivoted to said bolt and having engagement with said throw-plate and said catch, substantially as set forth.

7. In a sliding-door lock, the combination 120 of a throw-plate, guide-ribs, ribs carried by said throw-plate riding on said guide-ribs, a 125 slidable bolt, a spring-pressed catch pivoted

to said bolt, and a trigger pivoted to said bolt and having engagement with said throw-plate and said catch, substantially as set forth.

8. In a sliding-door lock, the combination 5 of a throw-plate, a rib carried by said plate, a slidable bolt, a catch pivoted to said slid- able bolt, a trigger pivoted to said bolt and having engagement with said throw-plate and said catch, and a retaining-bolt to engage said 10 throw-plate, substantially as set forth.

9. In a sliding-door lock, the combination of a throw-plate, a slidable bolt, a catch piv-

oted to said bolt, a trigger pivoted to said bolt and having engagement with said throw-plate and said catch, a notched rib adjacent to said 15 throw-plate, and a turn-button having a finger to enter the notch in said rib for the purpose of preventing movement of said throw- plate, substantially as set forth.

EDWARD MCKEAN.

In presence of—

A. V. ALEXANDER,
E. S. KNIGHT.
